UNITED STATES PATENT OFFICE

115,136

DESIGN FOR A COOLER CABINET OR THE LIKE

Walter F. Vose, Chicago, Ill., assignor to J. P. Seeburg Corporation, Chicago, Ill., a corporation of Illinois

Application March 20, 1939, Serial No. 83,698

Term of patent 7 years

To all whom it may concern:

Be it known that I, Walter F. Vose, a citizen of the United States and a resident of Chicago, in the county of Cook and State of Illinois, have invented a new, original, and ornamental Design for a Cooler Cabinet or the like, of which the following is a specification, reference being had to the accompanying drawing, forming a part thereof.

cabinet or the like showing my new design, and Figure 2 is a rear perspective view thereof, on a reduced scale.

The dominant features of my design reside in the parts shown by solid lines on the drawing.

I claim:

The ornamental design for a cooler cabinet or the like, substantially as shown and described.

WALTER F. VOSE.
